WO 2015108656 A1 7/2015

* cited by examiner

Primary Examiner — Antoine Duval Davis(74) *Attorney, Agent, or Firm* — Husch Blackwell LLP(57) **CLAIM**

I claim the ornamental design for a tee housing for ultrasonic sensor module, as shown and described.

DESCRIPTION

FIG. 1 is a front perspective view of a tee housing for an ultrasonic sensor module showing my new design;

FIG. 2 is a left elevation view thereof;

FIG. 3 is a right elevation view thereof;

FIG. 4 is a rear elevation view thereof;

FIG. 5 is a front elevation view thereof;

FIG. 6 is a top plan view thereof; and,

FIG. 7 is a bottom plan view thereof.
